UNITED STATES PATENT OFFICE.

BLASIUS BART, OF EAST ORANGE, NEW JERSEY.

METHOD OF FORMING METAL REFLECTORS AND APPARATUS THEREFOR.

Application filed September 23, 1921. Serial No. 502,679.

To all whom it may concern:

Be it known that I, BLASIUS BART, a citizen of the Republic of Switzerland, and resident of East Orange, in the county of 5 Essex and State of New Jersey, have invented certain new and useful Improvements in Methods of Forming Metal Reflectors and Apparatus Therefor, of which the following is a specification.

10 My invention relates to an improved form of metallic reflector of the type now used in flash-lights, search-lights and similar light reflecting articles, and the invention also relates to an improved method for 15 forming such reflectors and to an instrumentality for practicing the method economically.

There is a demand in the market at present for a form of reflector which can be 20 manufactured cheaply and therefore with the use of a relatively small amount of material and with a minimum amount of labor. The manufacturing problem is further complicated by the requirement that such reflector be provided with a threaded socket 25 for receiving the electric light bulb and some manufacturers of search-lights require an attaching flange or similar means for mounting the reflector in position in the 30 frame or other support.

It has been suggested in applicant's co-pending application, Serial No. 387,974, filed June 10, 1920 and Serial No. 387,975, filed June 10, 1920 to form reflectors by 35 spraying a solution of a silver salt onto a polished glass mold and to reinforce the thin film of reflecting metal by means of a backing of strengthening material such as copper, electrolytically deposited on the film 40 of reflecting material while positioned on the mold. It is a vital requirement of this process that the glass mold be chemically clean and highly polished in order to properly receive the layer of reflecting material. 45 This is particularly true when the material is nascently reduced silver.

Accordingly, one of the objects of the present invention is to provide for the formation of a reflector by practicing the method outlined with its necessity for a polished mold and at the same time form the required socket and attaching flange demanded by the search light manufacturer. 50 This phase of the invention is attained by 55 providing a glass mold in which the silver deposit receiving surface is continuous with-

out projections and thus capable of being formed initially and also capable of being polished from time to time as is required by the practicing of the method outlined. 60 Where the socket is to be formed the mold is provided with an opening extending therethrough and which of course does not interfere with the polishing process. It will be understood that a mold provided 65 with the necessary projections to form sockets, flanges and the like, would interfere with the polishing operation of the mold. The socket required is preformed preferably as a stamping from sheet metal, 70 is positioned at the opening and incidentally constitutes part of the means for mounting the mold in position. With the mold held by means engaging the opening and with the socket located in position the suggested 75 process of depositing the silver on the polished mold is practiced. Afterwards the mold with its silver deposit surrounding the socket is positioned in an electrolytic tank and in this case it is further suggested that 80 the support of the mold constitute the conductor for carrying current to the mold. A layer of backening material, such as copper is deposited on the sprayed silver layer which copper deposit is continued across the 85 socket, thus constituting a means for securing the socket permanently in place in the finished reflector. For the purpose of forming the attaching flange it is suggested that an outlining rim be demountably fitted to 90 the previously polished surface of the mold and the electrolytically deposited backing be continued across the rim to form the required outwardly projecting fastening 95 means.

Referring to the apparatus feature of the disclosure, an object of the invention is to provide a simple form of mold construction in which the different parts are readily demountable, particularly for the purpose of 100 cleaning and polishing the glass mold which forms a part of the construction, and at the same time to provide a single piece of apparatus which can be utilized with its assembled parts during the act of depositing 105 the reflecting material, and which can also be utilized to support and convey current to the parts of the electrolytic tank during the step of forming the backing layer.

Referring to the article of manufacture 110 phase of the disclosure, an object of the invention is to provide a reflector which may

include projecting parts, such as an electric light bulb mounting socket and a securing flange. It is also required that the reflectors be formed of a comparatively small amount of material; that all of the reflectors shall be uniform in appearance and that they be constructed without necessity for any refined machining or expensive manual labor in the process of forming the same.

10 Referring to the accompanying drawings there is disclosed a preferred embodiment of the physical aspects of the invention.

15 Figure 1 is a vertical sectional view taken axially through one of a set of mold structures showing the completed reflector in full outline, after it has been rotated from its dotted line position in the electrolytic tank; and

20 Figure 2 is a sectional view taken axially through a finished reflector slightly modified from the form shown in Figure 1 removed from the mold construction.

25 In the drawings, there is shown an electrolytic tank 10 containing an electrolyte 11 on which tank is positioned a combined mold support and conducting rod 12. It is understood that in electrolytic work the tank is of some material length and the single support 12 has a plurality of mold structures positioned along the length thereof. These structures are designed to be turned down into the electrolyte as shown in dotted lines or to be secured in their upright position shown in Figure 1 during the 35 act of depositing the silver on the molds. However, a usual practice is to mount the support 12 on a work table during the process of assembling the mold and depositing the silver on the same. A collar 14 is 40 fixed to the rod 12 and is provided with a threaded bore 15 into which is inserted one end of a brass plug 16, which projects laterally from the support 12. The plug is provided adjacent its opposite end with a stop 45 shoulder 17 and the portion beyond the shoulder is screw threaded as shown at 18. A semi-spherical hollow glass mold 19 is provided at its apex with an opening 20, of a size to receive the threaded end of the 50 plug. The parts are so proportioned that the mold is disposed in position with the part thereof surrounding the opening resting on the stop shoulder 17 and the mold is temporarily secured to the plug 16 by means 55 of a cap or socket 21 screwed onto the portion 18 of the plug. The cap is provided with an outstanding flange 22 which bears on the outer convex side 23 of the glass mold to force the same into engagement 60 with the stop shoulder 17. The threaded socket is preformed preferably by stamping from sheet metal and has a size and pitch of thread to accommodate whatever type 65 of electric light bulb socket it is desired to screw into the completed reflector. The free

edge 24 of the glass mold is outlined by a rim 25 of non-conducting material preferably "bakelite". The inner periphery 26 of the rim is curved and shaped to snugly fit the glass mold and thus provide a closed joint between the glass mold and the bakelite rim. The side 27 of the rim adjacent the metal receiving portion of the mold has a width and is shaped to correspond to the width and shape of the securing flange 28 desired on the completed article.

70 The device thus far described may be regarded as a complete reflector with a single lamp screwed into the socket at the apex of the same.

80 Under some conditions, such for instance, as where it is desired to mount a dim lamp in the reflector an additional socket 29 is secured in place usually between the apex and periphery of the reflector. In order to show a form of cap different from the cap 21, the socket 29 is not threaded and is simply an open end tube. For the purpose of disclosing a means for securing either socket or cap in place by a means different 85 from the plug 16 there is disclosed a bolt 30 passed through the mold and secured in place by a nut 31. The bolt is provided with a mushroom head 32 which bears at its central part on the outer end of the tubular lamp socket 29 and has a peripheral shoulder 33 which acts to prevent the copper backing from coming up to the top of the socket during the electrolytic depositing step of the 90 method.

100 In this form of the lamp mounting it may be considered that the lamp is secured in the socket 29 in any usual manner, for instance, the socket may be the usual casing of the lamp bases now in general use.

105 The outer convex face of the glass mold is polished over its entire surface either manually or by means of a machine constructed for this purpose. It is appreciated that the surface of the mold polished is continuous and therefore is susceptible of being cleaned and polished without leaving re-entrance angles or other inaccessible portions. The polished mold is then positioned 110 with the outer end of the plug extending through the opening, care being taken at this time that the polished surface is not touched by the hand of the operator, otherwise the silver deposit will not adhere to the touched parts. The threaded socket is 115 screwed into position binding the mold against the stop shoulder and bringing the flange of the socket into bearing engagement with the polished portion of the glass mold surrounding the opening. The bakelite rim is then disposed in position and forced into snug engagement with the glass mold.

120 A mixture of silver salts and a reducing 130 agent therefore is sprayed onto the exposed

portion of the polished glass in the manner more particularly defined in the above identified applications. The silver deposit is continued up the threads of the flange on 5 the socket and up to the flange forming the rim. When the desired thickness of silver deposit is formed the assembled structure is disposed in the electrolytic tank. Preferably the support 12, collar 15, plug 16, are 10 formed of some conducting material such as brass and thus constitute a means for conveying current to the parts to be coated as is usual in electrolytic operations of this character.

15 It is appreciated that one homogeneous layer of backing material, such as copper, is formed and that this backing extends continuously and integrally across the rim to form the securing flange, across the silver 20 deposit to reinforce the same and across the socket to secure the socket permanently in position relative to the reflecting surface in the completed reflector.

Having thus described my invention, I 25 claim:

1. In the art of forming a metallic reflector with a threaded socket for receiving the light bulb, the method which consists in 30 assembling a glass mold with an opening therethrough, inserting a threaded plug in said opening, screwing a preformed threaded socket onto the plug and forcing the plug into bearing engagement with the part of the mold outlining the opening, depositing a 35 layer of silver on the mold, extending the layer up to the preformed socket and covering the silvered surface and the socket with a backing of copper electrolytically deposited to give strength to the reflector and to 40 secure the preformed socket in place.

2. In the art of forming a metallic reflector with a threaded socket for receiving the light bulb and with an outlining flange, the method which consists in assembling a glass 45 mold with an opening therethrough, inserting a threaded plug in said opening, screwing a preformed threaded socket onto the plug and forcing the plug into bearing engagement with the part of the mold outlining the opening, positioning a bakelite rim about the glass mold in spaced relation to the socket, depositing a layer of silver on the mold, extending the layer up to the preformed socket and covering the silvered surface and the socket with a backing of copper electrolytically deposited to give strength to the reflector and to secure the preformed socket in place, the socket and the side of the rim adjacent the silvered surface with a 50 layer of copper electrolytically deposited and separating the reflector thus formed from the glass mold and the rim.

3. In the art of forming a concaved metallic reflector with a threaded socket, the 55 method which consists in polishing a glass

mold over all parts which are to define the reflecting surface, positioning a preformed threaded socket on the polished surface, depositing a layer of a reflecting metal on the polished surface about the positioned socket, 70 and electrolytically depositing a layer of backing metal to the reflecting metal and socket, said layer being continuous across the joint between the reflecting metal and the socket whereby the backing acts to secure the 75 socket in place.

4. In the art of forming a metallic reflector with an outwardly extending flange at its free edge, the method which consists in 80 polishing the outer surface of a glass mold, fitting a rim of non-conducting material to the polished surface to form a close joint therewith, depositing a layer of a reflecting metal on the polished glass surface, electrolytically forming a layer of a metallic 85 backing on the reflecting surface, on the rim and across the joint therebetween, the portion on the rim forming the flange and the portion on the reflecting layer acting to strengthen the same, severing the formed 90 backing from the rim and removing the glass mold from the finished reflector.

5. In the art of forming an object which includes a non-continuous surface and an electrolytically deposited layer, the method which consists in providing a mold with a continuous surface capable of being polished, polishing said surface, depositing a layer of metal on the polished surface, mounting the mold in an electrolytic tank 95 by engaging a portion thereof which is not coated with the layer of metal and electrolytically depositing a layer of metal over the portion previously deposited layer and over the non-continuous surface. 100

6. In the art of preparing a mold for a metallic reflector which includes a threaded socket for receiving the light bulb, the method which consists in assembling a glass mold with an opening therethrough, inserting a threaded plug in said opening, screwing a preformed threaded socket onto the plug and forcing the plug into bearing engagement with the part of the mold outlining the opening, the jointure between said 115 part of the mold and the socket adapted to be covered with a layer of metal.

7. In the art of preparing a mold for use in forming a metallic reflector electrolytically, the method which consists in assembling a glass mold with an opening therethrough, positioning at said opening a preformed member which is to constitute a part of the finished reflector, temporarily securing said preformed member in place whereby said member is disposed in fixed position relative to the mold during a succeeding step of depositing metal on the mold and member. 120

8. In the art of forming metallic articles, 130

the method which consists in forming a glass mold polishing a face of the mold, positioning on the polished face of the mold a preformed member which is to constitute a part of the finished article, subjecting said polished surface of the mold and said member to a coating of metal deposited thereon to form the portion of the article defined by said polished face and to secure 10 the preformed member in place as part of the article so formed.

9. In the art of forming a metallic reflector, the method which consists in providing a glass mold having a deposit receiving surface continuous from edge to edge free of projections and capable of being polished, positioning on said surface a projection to modify the effect of the mold on the resulting reflector, depositing on the 15 mold a face layer of metal and electrolytically depositing on said face layer and on said projection a continuous backing layer of metal.

10. In the art of forming a metal article by electrolytic deposition, the method which consists in providing a mold, mounting on the mold a preformed object designed to modify the effect of the mold on the resulting article and subjecting both the mold and 25 object to a layer of metal deposited thereon electrolytically and removing the mold while permitting the object to remain as part of the article.

11. In a device of the class described, the combination of a support including a threaded plug provided with a stop shoulder, a glass mold provided with an opening for receiving the plug when engaging said shoulder, a preformed socket adapted to be temporarily 35 threaded on the plug and acting to clamp the mold to the support, said mold and plug coacting to define the shape of the finished article and said plug adapted to be unscrewed from the finished article leaving the 40 socket in place.

12. In a device of the class described, the combination of a glass mold having a surface capable of being polished and having an opening extending through the polishable surface and means engaging said opening for supporting the mold in an electrolytic tank.

13. In a device of the class described, the combination of a glass mold having a substantially semispherical convex surface capable of being polished and having an opening at the apex, a support extending through the opening and adapted to hold the polished mold in position to receive a metallic deposit on the polished surface.

14. In a device of the class described, the combination of a glass mold having a substantially semispherical convex surface capable of being polished and having an opening at the apex, a support extending through

the opening and adapted to hold the polished mold in position to receive a metallic deposit on the polished surface, said support constituting an electric conductor adapted to position the mold in an electrolytic tank and to carry an electric current to the same. 70

15. In a device of the class described, the combination of a conducting rod constituting a means for supporting the device in an electrolytic tank, a plug having one end screwed into said rod, a glass mold carried by said plug and means for temporarily securing the mold to the plug. 75

16. In a device of the class described, the combination of a conducting rod constituting a means for supporting the device in an electrolytic tank, a plug having one end screwed into said rod, a glass mold carried by said plug, means for temporarily securing the mold to the plug and a reflector formed on said mold, said reflector including a part of said securing means. 80

17. In a device of the class described, the combination of a plug having a stop shoulder and a threaded portion adjacent the shoulder, a mold engaging said shoulder, a socket threaded on the plug and bearing on the mold to secure the same temporarily to the plug, a layer of reflecting material on the mold and a backing layer on the reflecting material extending over the socket to secure the same permanently to the layer of reflecting material. 85

18. In a device of the class described, the combination of a plug having a stop shoulder and a threaded portion adjacent the shoulder, a mold engaging said shoulder, a socket threaded on the plug and bearing on the mold to secure the same temporarily to the plug, a layer of reflecting material on the mold, a backing layer on the reflecting material extending over the socket to secure the same permanently to the layer of reflecting material and means encircling the 100 mold for defining the shape of the backing layer. 105

19. In a device of the class described, the combination of a semi-spherical glass mold having an opening at the apex, a support positioned in said opening and a rim encircling the mold adjacent its free edge, said rim and support being readily removable from the glass mold to permit the same to be polished. 110

20. In a device of the class described, the combination of a semi-spherical glass mold having an opening at the apex, means for securing a threaded socket in position facing said opening, a support positioned in said openings and a rim encircling the mold adjacent its free edge, said rim and support being readily removable from the glass mold to permit the same to be polished. 115

21. In a device for forming a metallic re- 120

flector, the combination of a conducting rod, a metallic collar secured to the rod, a metallic plug screwed into the collar, a glass mold carried by the plug and a socket threaded on said plug and engaging the mold.

22. In a device for forming a metallic reflector, the combination of a conducting rod, a metallic collar secured to the rod, a metallic plug screwed into the collar, a glass mold carried by the plug, a socket threaded on said plug and engaging the mold and a

rim outlining the free edge of the mold, said mold, rim and socket coacting to define the shape of the completed reflector.

15

23. A glass mold for use in forming metallic reflectors, said mold provided with a surface adapted to be polished, and provided with an opening extending therethrough and through said surface.

20

Signed at New York city, in the county of New York and State of New York, this 12th day of September, A. D. 1921.

BLASIUS BART.
